CLAIM

The ornamental design for a four-wheel vehicle, as shown and described.

DESCRIPTION

FIG. 1 is a top, front perspective view of a four-wheel vehicle showing my new design;

FIG. 2 is a rear, bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side view thereof;

FIG. 8 is a right side view thereof;

FIG. 9 is a portion of the perspective view of FIG. 1 enlarged for magnification purposes;

FIG. 10 is another portion of the perspective view of FIG. 1 enlarged for magnification purposes;

FIG. 11 is the other portion of the perspective view of FIG. 1 enlarged for magnification purposes; and,

FIG. 12 is a portion of the perspective view of FIG. 2 enlarged for magnification purposes.

The broken lines depict portions of the four-wheel vehicle that form no part of the claimed design. The dot-dash lines on FIGS. 1, 2 and 9-12 define the bounds of the enlarged portions of FIGS. 1 and 2 and form no part of the claimed design.
